COMMUTATOR TRUING TOOL

Clifford M. Bickham and Carson T. Hardacre,
Hammond, Ind.

Application June 3, 1935, Serial No. 24,766

4 Claims.

(Cl. 82—4)

Our invention relates to the art of tools for truing commutators, and has for an object the provision of a self-centering rotatable tool adapted to be attached to the shafts of automobile starter motors and generators, and which is operable to true the commutators thereof. Another object is the provision in such a tool of novel means for regulating the rate of speed at which the work engaging element of the tool is fed to the work. Other objects will become apparent from the description, to those skilled in the art.

The present disclosure is illustrative of a preferred embodiment of the principles of our invention, and we desire it to be understood that the invention is capable of all such changes in structural detail as will fall within the scope of the invention as claimed. In the drawing:—

Figure 1 is a longitudinal section through the tool as arranged for application in service position.

Figure 2 is a section on the line 2—2 of Figure 1.

Figure 3 is a section on the line 3—3 of Figure 1.

Figure 4 is a section on the line 4—4 of Figure 1.

In Figure 1 the tool is shown as positioned for operative engagement with the commutator 12 of an automobile starter motor or generator, in either of which the armature shaft 13 extends free. The tool comprises a hollow tubular barrel 14 of uniform external diameter provided with an axial bore internally threaded at its inner or work engaging end to receive the threaded seat end of a chuck 15 operable in a known manner by means of the chuck nut 16 to engage over and make rigid connection with the end of the armature shaft 13, whereby the barrel is centered upon and extends axially of the armature shaft.

Substantially midway of the barrel the bore is enlarged to provide an oil chamber 17 extending to the outer end of the barrel. This chamber is closed at its inner end by a seal plug 18 having threaded seating engagement in the end of the oil chamber and the chamber is supplied with fluid, preferably oil, through a filling port in the seal plug, the port being normally closed by a removable closure element 19.

Axially slidable within the bore of the fluid chamber 17 through its outer end is a hollow tubular piston 20 having a valved head 21 seating an outwardly opening ball relief valve 22 maintained on its seat by a coiled spring 23 held by

a retaining pin 24 within the valve socket. A restricted bleeder groove 25 extends inwardly through the head from the ball valve seat, and at its outer end the barrel 14 carries a cap nut 26 threaded thereon and having a lateral stop flange 27.

At its outer end the piston 20 is closed by a threaded plug 28 having an outwardly projecting axial hollow shank 29 which provides a support for the inner race 30 of ball bearings 31 having their outer race 32 disposed within a retaining cup 33 detachably threaded as at 34 in the outer end of a hollow tube 35 concentric with the barrel 14 and slidably axially thereon as well as being rotatable with respect thereto by virtue of a bearing sleeve 36 carried by the tube 35, as by a shrunk fit, which is slidable and rotatable upon the barrel 14, its extent of outward slidable movement being limited by engagement with the stop flange 27 at the outer end of the barrel. At its inner end 38 the tube 35 carries a fly wheel 37, preferably integral therewith.

Axially movable within the piston 20 is a floating plunger 39 having an associated cup washer 40. The plunger is normally forced inwardly under the influence of an expansion spring 41 disposed between the end plug 28 and the plunger. At the outer end of the tool a driver head 42 is threaded into the outer end of the member 33, being adapted to be tightened against the outer ball race 32 to clamp it against the inner flange of the bearing cup member 33. The driver head is axially bored and is provided in its outer face with a countersunk socket 43 cross-slotted as at 44 for operative engagement with the pilot key 45 mounted in the chuck 46 of a conventional drill 47.

The fly wheel 37 provides a tool post portion 48 having a set screw 49 by which the shank 50 of a tool holder 51 is slidably adjustable in the post. The holder 51 mounts a work engaging bit 52 adjustable in the holder in the conventional manner of such devices.

In service, the chamber 17 having been supplied with the proper amount of fluid, the tool is attached by means of the chuck 15 so that the barrel 14 is rigidly secured to and centered upon the armature shaft 13, as in Figure 1. The tool bit 52 is then adjusted for proper engagement with the work, the commutator segments, the tube 35 and its associated elements being moved axially over the barrel 14 for proper location of the tool bit. Power is then applied to the driver head 42 to rotate the tube 35 and its associated tool bit mounting upon the barrel 14 and inward-

ly over the commutator segments. Any conventional electric or hand drill is used for power, with its pilot key operatively engaging the driver head to provide the power which acts not only to rotate the tool bit with respect to the commutator but also to feed the tool bit axially inward over the commutator at the same time. The ball bearings 31 and the sleeve bearing 36 insure free rotation of the driving member comprising the tube 35.

The speed at which the tool bit is fed to the work is maintained constant and steady by the compressing action of the piston 20 upon the fluid in the chamber 17 as the piston is forced axially inward within the barrel 14. The fluid discharges as a jet through the restricted bleeder groove 25 of the piston head valve, entering the interior of the piston and maintaining a hydraulic back pressure, the relief of which controls the rate of tool feed with respect to the work. The fluid entering the hollow piston displaces the floating plunger 39 against compression of the spring 41.

When retracting the tool, the tube 35 is slid axially outward over the support barrel 14 until the outer end of the bearing sleeve 36 abuts the stop flange 27 on the cap nut 26. This movement carries the piston 20 outwardly, whereupon the external pressure upon the valve 22 is relieved, permitting the valve to open outwardly of the piston head for discharge of the piston contained fluid under the positive expelling action of the plunger 39 driven by the expansion of spring 41.

The tool is adaptable for undercutting purposes, where the hydraulic governing means is not required. For such purposes the driver head 42 is removed, whereupon the tube 35 may be operated without imparting movement to the piston 20. The chuck 15 by reason of its detachable engagement with the support barrel is replaceable by similar chucks of different sizes, so that the tool is adaptable for use in connection with armature shafts of different diameters.

It is within the scope of our invention that the driven elements of the tool may be operated by the application of power from any suitable source or means and applied to any part of the assembly, although at present the application of an electric or hand drill to the driver head seems best suited to the purpose.

We claim:—

1. A commutator truing tool comprising an axially elongated cylindrical support, means for

attaching said support rigidly to an armature shaft to extend axially therefrom, a member freely circumferentially rotatable and freely axially reciprocable on said support, a commutator engageable tool carried by said member and movable therewith, a fluid chamber in said support, and piston means fixedly connected with one end of said member and movable within said chamber to govern work engaging slidable movement of said member on the support.

2. A commutator truing tool comprising a tubular barrel, a chuck at one end thereof for rigid connection axially to an armature shaft, a tubular member slidable axially on the barrel and rotatable thereon, a commutator engageable tool carried by said member and movable therewith, said barrel having a bore providing a fluid chamber, a hollow piston associated with said tubular member and operable within said chamber by movement of said member whereby to compress fluid within the chamber upon work engaging movement of said member, and said piston having a restricted passage in its head to permit entry of fluid within the piston during work engaging travel of said tubular member.

3. A commutator truing tool comprising a tubular barrel, a chuck at one end thereof for rigid connection axially to an armature shaft, a tubular member slidable axially on said barrel and rotatable thereon, a commutator engageable tool carried by said member and movable therewith, said barrel having a bore provided with a fluid chamber, a hollow piston associated with said tubular member and operable within said chamber by movement of said member whereby to compress fluid in the chamber upon work engaging movement of said member, means for bleeding compressed fluid from the chamber to the interior of the piston during work engaging travel of said member, and means for expelling fluid from the piston to the chamber upon retractive travel of said member.

4. A commutator truing tool comprising an axially elongated cylindrical barrel open at one end and having in said end a chuck, an axially elongated sleeve freely slidable axially of the barrel and freely rotatable thereon, a tool mount on said sleeve, a member on said sleeve projecting axially within said barrel, and means in said barrel in cooperation therewith to regulate the speed of axial travel of said sleeve when moved axially over the barrel.
